UNITED STATES PATENT OFFICE

102,597

DESIGN FOR A CHARM OR SIMILAR ARTICLE OF JEWELRY

Felix B. Vollman, Rockaway Park, N. Y.

Application March 30, 1935, Serial No. 56,139

Term of patent 14 years

To all whom it may concern:

Be it known that I, Felix B. Vollman, a citizen of the United States and a resident of Rockaway Park, in the county of Queens and State of New York, have invented a new, original, and ornamental Design for a Charm or Similar Article of Jewelry, as shown, of which the following is a specification, reference being had to the accompanying drawing, forming a part thereof.

Figure 1 is a plan view of the charm or similar article of jewelry showing my new design, the material being formed from precious or semi-precious metals or similar materials;

Figure 2 is an end elevation thereof.

The characteristic feature of the present design resides in the ornamental appearance of the charm obtained by the arrangement of the

letters shown in substantially rectangular form with the letter U placed vertically over the O and joined thereto, with the letter R placed vertically over the letter K, the vertical bar of the letter R disposed vertically over the vertical bar of a letter K, with the downwardly and outwardly extending leg of the letter R being directed toward and joined to the upwardly and outwardly extending arm of the letter K, and a loop disposed symmetrically over and joined to the upper ends of adjacent vertical bars of the letters U and R.

I claim:

The ornamental design for a charm or similar article of jewelry, as shown and described.

FELIX B. VOLLMAN.
